Inventor:
George Stohn,
by A. Dinger, Atty.

UNITED STATES PATENT OFFICE.

GEORG STOHN, OF STOLBERG, GERMANY.

MECHANICAL ROASTING FURNACE.

Application filed January 26, 1921. Serial No. 440,231.

To all whom it may concern:

Be it known that I, GEORG STOHN, citizen of the German Republic, and residing at Stolberg, Rheinland, Germany, have invented certain new and useful Improvements in a Mechanical Roasting Furnace (for which I have filed application for patent in Germany October 20, 1919), of which the following is a specification.

10 The invention relates to a mechanical furnace for roasting ores and more particularly to the type, which is known as the "Spirlet furnace" having several superposed roasting chambers, each of them consisting of 15 a stationary and a rotary hearth-plate, the latter being rotated from the periphery. In the known roasting furnaces of this kind a vertical shaft is provided, from which the movement of all the movable 20 hearth-plates is derived. This manner of operation, which obviously necessitates all the hearths to be worked uniformly, has shown such drawbacks in practice, that the 25 economical working of the furnace has been rendered impossible.

This difficulty is overcome by the present invention; it consists in providing the rotary hearth plates with separate driving devices, so that the same may be moved independently of each other. This manner of 30 operating the rotary hearth-plates and therefore the chambers of the furnace separately and independently leads to a perfect control and regulation of the furnace and to a far better metallurgical exploitation, than hitherto has been obtainable. The invention affords a perfect independence in the working of the various 35 parts of the furnace.

40 It is for instance possible to employ for any chamber at any time a desired speed of rotation; moreover the direction of rotation may be chosen as required, that is forward or backward rotation may be used.

45 In the working of the known furnaces of this kind it happens often, that the ore accumulates at certain points of the furnace.

If the speed of rotation of the individual 50 chambers is properly adjusted, as may be easily done by the present invention, accumulations will not occur, as the thickness of the ore layers in all the floors may be readily chosen as high as required. Such 55 accumulations have hitherto most unfavorably influenced the efficiency of the furnace, as the speed of rotation had to be chosen

so small as to enable the rabbles to control efficiently the conveyance of the ore at such points.

By regulating the speed it is also possible 60 to control the operation in each chamber according to the varying condition of the ore. Sometimes it may be necessary to temporarily stop one or more chambers, if for an instance the charging device does not work 65 uniformly.

Another kind of regulation may be required, if the ore is to be retained for a longer period within a certain chamber, for instance if the ore for the purpose of thorough 70 roasting is to be subjected for a longer time to the temperature of the heated hearth. In such a case the invention makes it possible to cause a certain chamber to move forward and backward by using a 75 suitable reversing gear.

The invention is particularly advantageous as regards the metallurgical working of the furnace. As the invention enables the working 80 of the furnace to be adjusted in accordance with the changing condition of the ore, the roasting is improved both as regards quantity and quality. The higher efficiency is chiefly due to the fact, that the most favorable height of the layer of the ore, the highest 85 possible speed of feed and the periodical change of direction of the rotation, may be attained quite independently in the various hearths.

As regards the life of the furnace, the invention 90 also presents considerable advantages, as the durability of the rabbles, which are inserted in the hearth-plates, is increased owing to the fact, that the layers of the ore may be maintained at a uniform thickness. 95

One construction illustrating the invention is shown diagrammatically in the accompanying drawings, of which

Fig. 1 is a vertical section and

Fig. 2 a top view of Fig. 1.

100

The roasting chambers a , a^1 , a^2 , a^3 , a^4 , a^5 , a^6 , a^7 consists of a fixed hearth-plate c and a rotating hearth-plate d ; rabbles i are inserted in both of them. The hearth-plates carry troughs f and shields e at the 105 outside, which shields enter into the troughs; the latter are filled with a suitable sealing material, for instance sand.

Each of the hearth-plates d is fitted with a toothed ring Z . The pinions h engage 110 with the toothed rings Z ; the pinions h are mounted on shafts b , which are driven in

any desired manner. There is always one driving mechanism b' applied to each rotating hearth. To support the rotating hearth-plates rollers r are provided at the 5 out-side of the hearth-plates d , the rollers being guided on rails s . The ore is fed through the opening g into the upper chamber a and transported by the rabbles i through the openings g^1 into the second 10 chamber a^1 and so on to the chamber a^7 , from where it is finally discharged.

I claim:

1. Mechanical roasting furnace having a series of superposed roasting chambers, each 15 consisting of a stationary hearth-plate and

a rotating hearth-plate, rotated from the periphery, the individual rotary hearth-plates being operated by separate and independent driving means.

2. Mechanical roasting furnace having a 20 series of superposed roasting chambers, each consisting of a stationary and a rotary hearth-plate, the individual rotary hearth-plates being operated by separate and independent driving means, the latter being provided with a reserving gear for forward and 25 backwards rotation of the hearth.

In testimony whereof I affix my signature.

GEORG STOHN.
